UNITED STATES PATENT OFFICE.

HENRY W. MUNDHENK, OF GILMAN, IOWA.

BANNER.

SPECIFICATION forming part of Letters Patent No. 447,696, dated March 3, 1891.

Application filed June 25, 1890. Serial No. 356,707. (No model.)

To all whom it may concern:

Be it known that I, HENRY W. MUNDHENK, a citizen of the United States, residing at Gilman, in the county of Marshall and State of Iowa, have invented certain new and useful Improvements in Banners; and I do hereby declare the following to be a full, clear, and exact description of the invention, such as will enable others skilled in the art to which it appertains to make and use the same.

My invention relates to banners adapted for use in campaigns, lodges, &c.; and the object of my invention is to produce a banner which can be readily drawn in and withdrawn from a suitable staff.

A further object is to produce an effective and cheap banner, and one that will be protected from dust, &c., when not in use; and with these objects in view my invention consists in the parts and combinations of parts, as will be more fully described, and pointed out in the claims.

In the accompanying drawings, Figure 1 is a front elevation of the banner as it would appear open. Fig. 2 is a view of the banner closed in the staff. Fig. 3 is a detail view. Fig. 4 is a modification.

A represents the outer casing or staff, the staff being bored or hollowed out according to the length of the banner to be used. The staff may be of any desired size or shape in order to suit it to the occasion for which it may be used, and may be made of wood, tin, papier-maché, or any other suitable material.

B represents the banner, which may be made of any suitable material and decorated to suit the occasion for which it is to be used.

C is a suitable ornament attached to the top of said staff.

bb are two pieces or braces secured to the sides of the banner. (Shown in dotted lines in Fig. 1.)

D is a base-block, to which are hinged in a suitable manner the braces bb. This base D is of the same configuration as the outside casing or staff, in order that it may slide up and down inside of the staff as the banner is opened and closed. Secured on this base D are two springs dd in a suitable manner, which abut against the braces bb; or, if pre-

ferred, an elastic cord d' may be secured to the corners b' b' of the banner and carried down and secured to the outside of the casing, as at a a.

E is the operating-rod, having a handle E'. 55 This operating-rod extends up through the base-block D a suitable distance according to the height of the banner, and the head-piece or ornament C is secured thereto. At b' the banner is secured to the operating-rod. 60

F F are suitable tassels secured to the banner. Secured to the head of the staff is a suitable drapery F, which may be of any desired style or pattern. It will be understood that the banner may be decorated according to the 65 occasion of its use.

The operation is as follows: The banner being closed, as shown in Fig. 2, the handle E', attached to the rod E, is shoved up, thus raising the base-block and the banner. As 70 soon as the banner is entirely out of the hollow staff, the elastic cords d' d' or the springs dd, whichever are used, forces the banner B open. The operation of closing the banner is obvious. In closing the banner finely-cut 75 tissue paper may be sprinkled in it, and when it is again opened the tissue paper flies to the breeze, thus making a fine display.

In Fig. 4 I have shown the banner in combination with a cane, and as the construction 80 and operation are substantially the same it is not deemed necessary to describe it apart from the rest of the views.

It is evident that many slight changes and alterations may be made in the relative construction and arrangement of parts without departing from the spirit of my invention, and hence I would have it understood that I do not confine myself strictly to the parts herein described. 85

Having fully described my invention, what I claim, and desire to secure by Letters Patent, is--

1. A hollow staff having a sliding block, a banner secured to said block, a rod for forcing said banner out of said staff, and an elastic connection adapted to spread the banner, substantially as described. 95

2. In combination with a hollow staff, a sliding block adapted to slide in said staff 100

and a banner hinged to said block, means for forcing said banner out of the staff, and an elastic connection with the block adapted to spread said banner open, substantially as described.

3. In combination with a hollow staff, a block D, adapted to slide therein, braces b b, hinged thereto, a banner secured to said braces, means for spreading said banner, an operating-rod E, secured to sliding block D and extending to the top of the banner, and a suitable head secured to rod D, substantially as described.

4. In combination with a hollow staff, a block sliding therein and banner hinged thereto, means for spreading said banner, an operating-rod D, secured to the sliding block and extending to the top of the banner, and a suitable decoration secured to the top of the staff, substantially as described.

In testimony whereof I affix my signature in presence of two witnesses.

HENRY W. MUNDHENK.
